UNITED STATES PATENT OFFICE.

THOMAS S. McELHOSE, OF PATERSON, NEW JERSEY.

STOP-MOTION FOR MACHINES FOR DOUBLING SILK AND OTHER FIBERS.

SPECIFICATION forming part of Letters Patent No. 289,117, dated November 27, 1883.

Application filed February 23, 1883. (No model.)

To all whom it may concern:

Be it known that I, THOMAS S. McELHOSE, of the city of Paterson, in the county of Passaic and State of New Jersey, have invented a new and useful Improvement in Stop-Motions for Machines for Doubling Silk and other Fibers, of which the following is a specification.

My invention relates to doubling-machines in which the head of the spindle of the winding-bobbin bears with its weight upon a driving-wheel, so as to be rotated by frictional contact with the latter, and is raised out of contact with said wheel by an automatic stop-motion upon the breaking or giving out of a strand, so as to stop the rotation of the bobbin.

The object of the invention is to obtain a more positive and prompt stoppage of the winding-bobbin in case of the breaking or giving out of the strands, or in case the bobbin becomes full.

In stop-motions of the kind above described there are used a drop-lever or faller and drop-wires or faller-wires. The drop-lever or faller is always so nicely balanced that the weight of a drop-wire failing on the lever or faller will cause it to tilt and aid in effecting the raising of the winding-bobbin.

My invention consists in the combination, with a winding-bobbin or a spindle and a driving-wheel serving to drive the bobbin by frictional engagement with the bobbin or its spindle-head of a slider-bar having an inclined or wedge-like upper surface for acting on the spindle to raise the bobbin, a spring for actuating the slider-bar to cause it to raise the spindle and bobbin, a catch for holding the slider-bar stationary in an operative position or set, and drop-wires and a drop-lever, the latter of which is adapted to engage with said catch for releasing the slider-bar, all as more fully hereinafter described. The tilting of the drop-lever under the weight of the drop-wire serves simply to bring the latter into a position to act on the catch and to be acted on by a tappet on the spindle or bobbin to raise the spindle and bobbin; and this tappet, in conjunction with the aforesaid elements, constitutes a part of my invention. The above-described combination serves only to raise the

winding-bobbin when a strand breaks or gives out; but my invention further consists in a novel combination of devices, whereby the bobbin or spindle will be raised out of contact with the driving-wheel when the bobbin 55 is full, as hereinafter particularly described.

The invention also consists in various details of construction and combinations of parts, hereinafter described, and pointed out in the claims.

In the accompanying drawings, Figure 1 is a vertical section of a portion of a machine embodying my invention. Figs. 2 and 3 are corresponding sectional views of a portion of the machine upon a larger scale, the former figure 65 showing the bobbin-head in an operative position, and the latter figure showing it in an inoperative position; and Fig. 4 is a plan view of the parts shown in Figs. 2 and 3 and upon the same scale.

Similar letters of reference designate corresponding parts in all the figures.

A designates a portion of one of the end frames of the machine, and A' designates one of the rails or stretchers connecting the end 75 frames.

B designates the spools from which the strands are taken, and which are arranged upon a board, B', and are surmounted by fliers a. From these spools and fliers the strands b are carried over the tension-rods c, and through the drop or faller wires d and traverse-bar e, to the winding-bobbin C. (Shown only in Fig. 1.) C is the spindle of the winding-bobbin. So far as described, the machine 85 possesses no particular novelty, but is very commonly used for the purpose of doubling silk, and it is customary to place a row of winding-bobbins on each side of the machine.

D designates a shaft extending lengthwise 90 of the machine and carrying wheels D', each of which is adapted to impart motion to a winding-bobbin by frictional engagement with the spindle-head C upon the spindle C.

E designates brackets or hangers, which extend from the rail A', and have formed in them open bearings f, wherein the spindle C of the winding-bobbin may turn. The spindle-head C rests with the weight due to the spindle and bobbin on the driving-wheel D', 100

and the open bearings permit the spindle to be raised to take its head out of contact with said driving-wheel.

In each bracket or hanger E is arranged a 5 slider-bar, F, which is provided with a horn or handle, F', whereby it may be drawn outward; and G designates a catch, which is pivoted at g, and provided with a shoulder, g', for engaging with a pin, g'', on the slider-bar, 10 for holding it in its outward position, as shown in Fig. 2.

In the upper surface of the slider-bar there is an incline or wedge, h, which is formed by a depression in the bar, and when the slider-bar is drawn out, so that the shoulder g' of the catch G engages with the pin g'', this hollow or depression is opposite or below the spindle C, and the latter can drop so that its head C' will rest upon the driving-wheel D'. When 20 the slider-bar is moved inward into the position shown in Fig. 3, the inclined surface h thereof raises the spindle, so as to take its head C' out of contact with the wheel D', and said spindle is supported upon the upper surface of the slider-bar.

Connected with the inner end of the slider-bar F is a rod, i, which plays in a guide, i', in the bracket E, and said rod is surrounded by a spiral spring, i'', which is compressed as 30 the slider-bar is pulled outward or set, and which exerts a constant tendency on said bar to move it inward. Consequently as soon as the catch g' is raised out of engagement with the pin g'', the slider-bar flies forward under 35 the impulse of the spring i'' and raises the spindle-head C' out of contact with its driving-wheel D'.

H H' designate a drop-lever or faller, which is pivoted in a fulcrum-piece, I, secured to a 40 rail, A''. One arm, H, of this lever extends into proximity with the end of the catch G, as shown in Figs. 3 and 4, and the other arm, H', is made of considerable width, and extends under the drop-wires or faller-wires d, as shown in Fig. 4. When the drop or faller wires are all held up by the strands b, as shown in Fig. 2, the arm H of the drop-lever or faller descends and rests upon the projecting portion j of the bracket E, as shown in Fig. 2. 45 When in this position, the slider-bar F is held outward by the shoulder g' of the catch G, and the spindle-head C' rests upon and is rotated by frictional contact with the driving-wheel D'.

Upon the end of the spindle-head C' is a 55 pin, k, constituting a tappet, and when the end of the arm H of the lever or faller rests upon the support j, this tappet passes over it without interference as the spindle-head C rotates. The drop-lever or faller H H' is so 60 nicely balanced that if one of the strands b breaks or runs out and its drop-wire or faller-wire d falls onto the arm H', the lever is tilted and its arm H is raised into contact with the end of the catch G. The rising of the arm H 65 might of itself serve to lift the catch G if properly organized. In the present instance,

however, the end of the arm H rises into contact with the end of the catch, and as the spindle-head C' continues its rotation its tappet k strikes against the under side of the arm H, and raises it and the catch G sufficiently to move the shoulder g' out of engagement with the pin g'', and allow the slider-bar F to shoot inward under the impulse of the spring i''. This raises the spindle-head C' out of contact 75 with the driving-wheel D' and stops the bobbin. After the strand is repaired or a new one entered, the drop-lever or faller H H' resumes the position shown in Fig. 2, and by pulling the slider-bar F outward by its handle F' it is again set for operation. The slider-bar constitutes a lifter or lifting device for raising the spindle.

In some machines the silk or other material on the winding-bobbin rests upon the driving-wheel D', and in such machines the operation would be the same, except that the bobbin, instead of the spindle-head, would be raised out of contact with the driving-wheel D' by the lifting action of the slider-bar F.

So far as described the mechanism does not provide for raising the bobbin when it becomes full, and I will now describe how this is effected.

J designates a rock-shaft fulcrumed or journaled in the brackets or hangers E, and provided with an upwardly-projecting arm, J', carrying a roller, J'', and also provided with a horizontally-extending arm, J'', which has a projection, l, extending under the drop-lever or faller, and a set-screw, m, in the end. The set-screw m limits the downward movement of the arm J'', and consequently regulates the distance from the spindle C and bobbin thereon to which the roller J'' can approach.

It is obvious that a pressure upon the roller J'' in a direction away from the spindle C will raise the arm J'', and through the projection l will lift the arm H of the drop-lever or faller against the catch G, so that at the next rotation of the spindle-head the tappet k will strike the said arm, and by raising it will release the slider-bar or lifter, and so stop the rotation of the winding-bobbin.

The roller J'' has a cam-face, n, or a portion of greatest projection, which may be produced in making the roller, or secured by attaching thereto a piece of leather or other material; and the roller is weighted or loaded on one side, so that it will stand normally in the position shown in Fig. 2. The roller J'' is arranged opposite the position which the bobbin C occupies, as shown in Fig. 1, and as the material increases on the bobbin, and as soon as it is full, the material will catch the roller J'', and, rotating it in the direction of the arrow, Fig. 2, will draw its portion of greatest projection or cam-face against the bobbin, and so force the arm J' backward or away from the spindle and lift the arm J'', to raise the drop-lever or faller-arm H. As soon as the bobbin is removed and a new one inserted, the roller

J^2 and the rock-shaft J and arm J^3 resume their normal position. (Shown in Fig. 2.) The rock-shaft J , with its arms J' J^3 , constitutes a lever carrying the roller J^2 .

5 It will be seen that by my invention I effect the stoppage of the winding-bobbin in a very positive manner and without any delay, and my invention is therefore of great utility.

What I claim as my invention, and desire to 10 secure by Letters Patent, is—

1. The combination, with a winding-bobbin or a spindle, C , and a driving-wheel, D' , serving to drive the bobbin by frictional engagement with the bobbin or its spindle-head, of a 15 slider-bar, F , having an inclined or wedge-like upper surface, h , for acting on the spindle to raise the bobbin, a spring, i , for actuating the slider-bar to cause it to raise the spindle and bobbin, a catch for holding the slider-bar 20 stationary in an operative position or set, and drop-wires and a drop-lever, the latter of which is adapted to engage with said catch for releasing said slider-bar, substantially as and for the purpose described.

2. The combination, with a winding-bobbin or spindle provided with a tappet and its driving-wheel, of a lifter or lifting device for raising the spindle and bobbin, a spring for actuating the lifter or lifting device to cause 25 it to raise the spindle and bobbin, a catch for holding said lifter or lifting device in an inoperative position or set, and drop-wires and a drop-lever, the latter of which is adapted to engage with said catch and to be acted upon 30 by the said tappet for throwing off the catch, substantially as and for the purpose described.

3. The combination of the winding-bobbin spindle C and head C' , provided with the tappet k , the driving-wheel D' , the brackets or 35 hangers E , the slider-bar F , provided with a wedge, h , and pin g^2 , the spring i^2 , the catch G , the drop-wires d and lever H H' , the rock-shaft J , the arm J' , and roller J^2 and the arm J^3 , and adjustable stop m , all substantially as described.

G, provided with the shoulder g' , and the drop-wires d and drop-lever H H' , all substantially as described.

4. The combination, with a winding-bobbin 45 or its spindle and its driving-wheel, of devices for raising said bobbin and spindle out of contact with said driving-wheel, a roller having a cam-face and loaded on one side of its center, so as to cause it to return to a predetermined 50 position after being turned, and a lever carrying said roller and controlling the operation of the devices for raising the bobbin and spindle, substantially as and for the purpose described.

5. The combination, with the bobbin or spindle and its driving-wheel, of a lifter or lifting device for raising the spindle and bobbin, a spring for actuating said lifter or lifting device to cause it to raise the spindle and bobbin, a catch for holding said lifter or lifting device in an inoperative position, drop-wires and a drop-lever, the latter of which is adapted to engage with said catch, a roller arranged so as to be operated on by the material wound on 60 the bobbin, and a lever carrying said roller and adapted to move said drop-lever to throw off the catch, substantially as and for the purpose described.

6. The combination of the spindle C , having 70 a head, C' , provided with the tappet k , the driving-wheel D' , the brackets or hangers E , the slider-bar F , provided with a wedge, h , and pin g^2 , the spring i^2 , the catch G , the drop-wires d and lever H H' , the rock-shaft J , the arm J' , and roller J^2 and the arm J^3 , and adjustable stop m , all substantially as described.
